UNITED STATES PATENT OFFICE

VERNER LINDSJO, OF HOPEDALE, MASSACHUSETTS, ASSIGNOR TO DRAPER CORPORATION, OF HOPEDALE, MASSACHUSETTS, A CORPORATION OF MAINE

CLOTH ROLL WIND-UP MECHANISM

Application filed October 21, 1929. Serial No. 401,077.

This invention relates to looms and particularly to the mechanism employed in the loom to manipulate the cloth roll. The invention has for its general object to provide a more convenient and flexible means to raise and lower the cloth roll and to adjust the tension of the yielding means which moves the cloth roll into position.

A further object of the invention is to provide a mechanism of the character above described having a removable operating handle which when in operative position will extend a convenient distance from the loom in order to be readily grasped by the operator.

The object of the invention is further to provide means operable to lock the wind-up mechanism against rotation when the operating handle is removed, said means being held out of locking engagement by the handle when in its operative position. Preferably, such means will act automatically to lock the shaft against rotation upon removal of the handle.

These and other objects and features will more fully appear from the following description in connection with the drawings and will be particularly pointed out in the claims.

In the drawings:

Fig. 1 is a front elevation of a loom embodying the principles of the invention.

Fig. 2 is a transverse sectional view on line 2—2 Fig. 1.

Only those elements of the loom directly associated with the improvements herein presented are illustrated. It is considered unnecessary to further describe the loom since those skilled in the art will readily perceive the adaptation of the present improvements to the loom in general. The present invention is particularly adapted to the type of loom in which the cloth roll is maintained in contact with the take-up roll and frictionally driven thereby and in which the cloth roll moves down as the cloth mass thereon increases in size.

In the particular embodiment shown a take-up roll 1 is journalled in the loom frame in the usual or any convenient manner and is driven in any suitable way as by means of

the gear 2 mounted on the take-up roll shaft. The gear 2 meshes with the usual take-up gear train not shown. The cloth roll 3 is located beneath the take-up roll and is supported in contact therewith by the rack bars 4 which are guided in the take-up stands 5 and 6 on either side of the loom. The upper ends of the rack bars are provided with bearings to receive the journals 7 and 8 of the cloth roll. The take-up stands are secured at their lower ends to the usual girt 9 extending across the loom between the loom sides 10 and 11. The take-up stands 5 and 6 are secured at their upper ends to the breast beam 12. A shaft 13 is journalled in the lower ends of the take-up stands 5 and 6 and has secured at each end thereof sprockets 14 and 15 over which pass respectively sprocket chains 16 and 17. The chain 16 extends upwardly and embraces a sprocket 18 while the chain 17 drives a sprocket 19. Gears 20 and 21 are secured to the sprockets 18 and 19 respectively with their axes in alinement. The sprocket 18 and the gear 20 are mounted for rotation upon a stud shaft 22 fixed in the take-up stand 5. The other sprocket 19 with its gear 21 are rotatably mounted on a stud shaft 23 fixed in the take-up stand 6. The stud shafts 22 and 23 are so positioned that the gears 20 and 21 mesh with the rack bars 4 on either side of the loom.

Situated intermediate of the sprockets 14 and 15 at the ends of the shaft 13 is a worm gear 24 loosely mounted on the shaft and to which is secured one end of a helical spring 25 surrounding the shaft. The other end of the spring is secured to a collar 26 rigid with the shaft. Journalled in the cross girder is a wind-up shaft 27 extending transversely of the cloth roll and the cross shaft 13. The wind-up shaft 27 has secured at one end a worm 28 which engages and drives the worm gear 24. To raise the cloth roll the shaft 27 is rotated thus rotating the worm gear 24 which results in tensioning the spring 25. The tension of the spring is transmitted through the collar 26 to the shaft 13 which is rotated thereby. The motion of the shaft is transmitted equally to

the rack bars 4 through the sprocket and chain connections to the gears 20 and 21 meshing with the rack bars. The cloth roll is thus raised and maintained in parallel relation to the take-up roll.

5 By means of the mechanism above described the cloth roll can be raised or lowered and the tension in the spring may be varied at will. As the mass of cloth on the cloth roll is built up the rack bars are forced 10 downwardly which results in rotating the shaft 13 to increase the tension in the spring since the gear 24 is held against rotation by engagement with the worm 28. This increased tension is desirable as it compensates 15 for the increased weight of the roll as more cloth is wound thereon and thus maintains a substantially uniform pressure of the cloth roll with the take-up roll. At all times during the operation of the loom there is a substantial torque tending to rotate the gear 24. This torque increases as the mass of cloth is built up and reaches its maximum 20 when the cloth roll has received all that it can take. The worm 28 meshing with the gear 24 resists this torque and under certain conditions completely prevents rotation of the gear. During the operation of the loom however there is always a certain amount 25 of vibration. The effect of this vibration is to slowly rotate the wind-up shaft. The friction between the worm and worm gear is normally sufficient to prevent rotation of the wind-up shaft. The vibration however 30 breaks down this friction to a certain extent and establishes a slow drive which if permitted to act would eventually lower the cloth roll which obviously is an undesirable condition.

40 The present invention aims to prevent this rotation of the wind-up shaft by locking it in a novel and positive manner. The shaft 27 passes through the girder 9 and is supported in bearings 29 and 30 secured to the front and rear faces of the girt 9. A sleeve 45 31 is secured at the front end of the shaft 27 by means of a set screw 32. A semi-cylindrical portion is removed from the front end of the shaft 27 to provide a driving connection with an operating handle hereinafter 50 to be described. Any other convenient means may be employed to establish this connection. The sleeve 31 extends beyond the front end of the shaft 27 to form a recess 33 which receives an extension shaft 34 55 upon the end of which is an operating handle 35. The inner end of the extension shaft is shaped complementary to that of the end of the shaft 27 so that when the ends of the shafts are in engagement a driving connection 60 is established therebetween. Extending substantially horizontally from the lower portion of the bearings 29 are a pair of ears 36 between which is pivoted a latch 65 member 37. Cooperating with the latch are

a plurality of notches 38 in the end of the sleeve 31.

The latch member is so positioned relative to the extension shaft that when the shaft is in operative position the end of the latch engages said shaft and is held out of engagement with the notches as shown in dotted lines in Fig. 2. When the handle is in this position therefore the latch cannot act to lock the shaft 27. When the handle is removed however the latch may be swung into position to engage a notch in the sleeve thus locking the shaft against rotation. The latch member may have any desirable form but preferably is constructed to act automatically upon removal of the handle to prevent rotation of the shaft. In the embodiment herein disclosed the latch is gravity-operated. A weighted arm 40 extends below and to the rear of the pivot point 39 and upon removal of the shaft acts automatically to move the latch into engagement with the end of the sleeve and when the shaft rotates sufficiently into one of the notches in the sleeve.

90 Any suitable form of wind-up shaft may be employed with or without an extension shaft. The particular mechanism shown is adapted for use on a loom where it is contemplated to build up a cloth roll to a size limited only by the position of the girder 9 as indicated by the curved dotted line in Fig. 2. Under such circumstances it becomes difficult to reach under the roll to manipulate the wind-up shaft. It becomes desirable therefore to provide an extension so that the handle will be in a convenient position. This extension may be as long as desired since it is normally removed from the loom and is used only when the operator desires to raise or lower the cloth roll. Upon removal of the handle and its extension shaft the latch is permitted to engage the sleeve under the action of the weighted arm 40. If the vibration of the loom tends to rotate the wind-up shaft it can only move until a notch in the sleeve registers with the latch at which time the latch will enter the notch and positively lock the shaft against further movement.

100 Having thus described the invention, what is claimed as new, and desired to be secured by Letters Patent, is:

1. A loom comprising a driven take-up roll, a cloth roll upon which the cloth is wound by the frictional engagement of the cloth mass thereon with the take-up roll, a wind-up shaft journaled in the loom, yielding connections between the shaft and the cloth roll for raising and lowering the cloth roll when the shaft is rotated and for permitting the cloth roll to move down as the cloth is wound thereon without rotating the shaft, a handle removably connectible to the shaft for rotating it, and means operable to lock the 110 120 125 130

shaft against rotation upon removal of the handle.

2. A loom comprising a driven take-up roll, a cloth roll upon which the cloth is wound by the frictional engagement of the cloth mass thereon with the take-up roll, a wind-up shaft journalled in the loom transversely of and beneath the cloth roll, yielding connections between the shaft and the cloth roll for raising and lowering the cloth roll when the shaft is rotated and for permitting the cloth roll to move down as the cloth is wound thereon without rotating the shaft, a handle removably connectible to the shaft for rotating it, and means acting automatically to lock the shaft against rotation upon removal of the handle.

3. A loom comprising a driven take-up roll, a cloth roll upon which the cloth is wound by the frictional engagement of the cloth mass thereon with the take-up roll, a wind-up shaft journalled in the loom transversely of and beneath the cloth roll, yielding connections between the shaft and the cloth roll for raising and lowering the cloth roll when the shaft is rotated and for permitting the cloth roll to move down as the cloth is wound thereon without rotating the shaft, a handle removably connectible to the shaft for rotating it, and means acting automatically to lock the shaft against rotation upon removal of the handle.

4. A loom comprising a driven take-up roll, a cloth roll upon which the cloth is wound by the frictional engagement of the cloth mass thereon with the take-up roll, a wind-up shaft journalled in the loom transversely of and beneath the cloth roll, yielding connections between the shaft and the cloth roll for raising and lowering the cloth roll when the shaft is rotated and for permitting the cloth roll to move down as the cloth is wound thereon without rotating the shaft, a handle removably connectible to the shaft for rotating it, and a latch pivoted on the loom operable to prevent rotation of the shaft when the handle is removed therefrom.

5. A loom comprising a driven take-up roll, a cloth roll upon which the cloth is wound by frictional engagement of the cloth mass thereon with the take-up roll, a wind-up shaft journalled in the loom transversely of and beneath the cloth roll, yielding connections between the shaft and the cloth roll for raising and lowering the cloth roll when the shaft is rotated and for permitting the cloth roll to move down as the cloth is wound thereon without rotating the shaft, a handle removably connectible to the shaft for rotating it, a latch pivoted on the loom adjacent the end of said shaft acting to lock said shaft against rotation upon removal of

said handle extension and held out of locking engagement by said handle extension when it is in its operating position.

6. A loom comprising a driven take-up roll, a cloth roll upon which the cloth is wound by the frictional engagement of the cloth mass thereon with the take-up roll, a wind-up shaft journalled in the loom transversely of and beneath the cloth roll, yielding connections between the shaft and the cloth roll for raising and lowering the cloth roll when the shaft is rotated and for permitting the cloth roll to move down as the cloth is wound thereon without rotating the shaft, a handle removably connectible to the shaft for rotating it, a sleeve on the shaft open at its end to receive the handle, a latch pivoted upon the loom acting to lock the shaft against rotation by engagement with the end of said sleeve upon removal of the handle.

7. A loom comprising a driven take-up roll, a cloth roll upon which the cloth is wound by the frictional engagement of the cloth mass thereon with the take-up roll, a wind-up shaft journalled in the loom transversely of and beneath the cloth roll, yielding connections between the shaft and the cloth roll for raising and lowering the cloth roll when the shaft is rotated and for permitting the cloth roll to move down as the cloth is wound thereon without rotating the shaft, a handle removably connectible to the shaft for rotating it, a sleeve on the shaft open at its end to receive the handle and having notches therein, a gravity actuated latch pivoted upon the loom acting to lock the shaft against rotation by engagement with said notches upon removal of the handle.

In testimony whereof, I have signed my name to this specification.

VERNER LINDSJO.
